DESIGN FOR A PLAYGROUND APPARATUS

Carl D. Spangler, Oklahoma City, Okla.

Application March 18, 1937, Serial No. 68,259

Term of patent 7 years

To all whom it may concern:

Be it known that I, Carl D. Spangler, a citizen of the United States, residing at Oklahoma City, in the county of Oklahoma and State of Oklahoma, have invented a new, original, and ornamental Design for a Playground Apparatus, of which the following is a specification, reference being had to the accompanying drawing, forming part thereof.

The figure is a perspective view of a playground apparatus, showing my new design.

The dominant feature of my design resides in the frame member shown in full lines in the illustration.

I claim:

The ornamental design for a playground apparatus, as shown, and described.

CARL D. SPANGLER.
